UNITED STATES PATENT OFFICE.

CANAAN DE CAZEN, OF MONTREAL, QUEBEC, CANADA.

CIGARETTE-MAKING MACHINE.

1,078,034.

Specification of Letters Patent. Patented Nov. 11, 1913.

Application filed February 2, 1911. Serial No. 666,173.

To all whom it may concern:

Be it known that I, CANAAN DE CAZEN, a subject of the King of Great Britain, and resident of 425 Duluth avenue east, in the city and District of Montreal, Province of Quebec, Dominion of Canada, have invented certain new and useful Improvements in Cigarette-Making Machines; and I do hereby declare that the following is a full, clear, and exact description of the same.

The invention relates to improvements in cigarette making machines, as described in the present specification and illustrated in the accompanying drawings that form part of the same.

The invention consists essentially of the novel construction and arrangement of parts, whereby the tobacco is evenly distributed in the hopper by regulating devices coacting with an endless carrier and automatically transported, formed and cut into suitable lengths.

The objects of the invention are to devise in such machines, smoothness and consequently speed in all the automatic parts thereto, to increase the output at a minimum expenditure of power, to furnish a machine of compact form and generally to provide a simple, cheap and durable construction.

In the drawings, Figure 1 is a side elevation of the machine partly in longitudinal section, showing the operating connections. Fig. 2 is a plan view of the machine from above. Fig. 3 is a cross sectional view on the line A—B in Fig. 1. Fig. 4 is a cross sectional view on the line C—D in Fig. 1. Fig. 5 is an enlarged perspective detail of the shearing mechanism and table. Fig. 6 is an enlarged perspective detail of a portion of the shearing mechanism showing particularly the approach in a modified arrangement of arresting for cutting purposes. Fig. 7 is an enlarged perspective detail of the knife and the means employed for sharpening. Fig. 8 is an enlarged perspective detail of the regulating scraper in the feed mechanism. Fig. 9 is a plan view of an adjustable eccentric shown in this invention. Fig. 10 is an enlarged perspective detail of the friction wheel and the adjusting mechanism. Fig. 11 is an enlarged perspective detail of the shield and the feed mechanism.

Like numerals of reference indicate corresponding parts in each figure.

Referring to the drawings, 1 is an endless belt, forming the tobacco carrier and having the forwardly projecting picks 2, rigidly secured therein and extending outwardly from the surface thereof.

3 and 4 are the rollers around which the carrier 1 extends, the roller 3 being a driving roller and said rollers being mounted on the shafts 5 and 6.

7 is a hopper box into which the endless carrier 1 conveniently fits, said box having the bearings 8 and 9 for the shafts 5 and 6 in the sides thereof and a flaring top 10.

The shaft 5 projects outwardly beyond the bearing 8 and carries at its outer end the worm wheel 11.

12 are slide-ways secured to the inner wall of the box on each side thereof, just above the carrier 1 toward the delivery end, that is to say, toward the roller 3.

13 is a comb formed of the frame 14, said frame forming the back of the comb and the strips 15 forming the teeth of the comb, said strips 15 being hinged to the under side of the plate in an ordinary form of barrel and pin hinge, the center portion 16 of the barrel being integral in each case with the plate 14 and the end portions 17 with the strips 15, said end portions extending laterally from the strips at the upper and outer sides thereof, so that when the pins 18 are inserted through the barrel portions 16 and 17, the strips 15 will only fold one way and will be perfectly rigid the other way, that is to say, the top of the strip in the end portion 17 will abut the bottom of the plate 14 when said plate 14 is moved in a forward direction. The strips 15 or the teeth portion of the comb are here shown with toothed edges, that is to say, with a serrated edge or other formation, but it will be readily understood that they may be made in any suitable shape.

The frame 14 is mounted in the slide-ways 12, so that the strips 15 reach down and terminate just over the picks 2 and the forward direction of travel of said plate is in the opposite direction to the travel of the upper portion of said belt 1, consequently the comb 13 moves over the tobacco carried by the carrier 1 and combs back the surplus.

In the backward movement of the comb 13, the teeth portion or strips 15 must turn on their hinges and idly travel over the tobacco.

- 19 is a rotary brush having the bristles 20 and mounted on the shaft 21, said shaft bearing journaled in the extensions 22 of the side walls of said hopper box 7. The bristles 20 of the rotary brush 19 extend over to the end of the carrier 1, which passes over the roller 3, consequently in driving the brush 19, the bristles 20 sweep the tobacco clean from the carrier 1 and deposit it in the funnel-shaped hopper 23, said funnel-shaped hopper having a large wide mouth 24 at the bottom and preferably forming part with the extensions 22.
- 26 is a sprocket wheel fixedly mounted on the extending end of the shaft 21.
- 27 is the former supported on the table 28 and extending therebeyond at the forward end under the funnel hopper 23 and open or slightly trough-shaped at that point 20 and extending along on the table gradually closing, leaving the slit 29 open so that one side of the paper may project out to receive the adhesive from the roller 30, said roller being connected with a paste pot 31 suitably operated. This really has very little to do with this invention as any suitable form of pasting device may be used. The former is in tube like form, beyond the slit 29 and terminates at 32.
- 33 are brackets forming bearings for the roller 34, said roller 34 being in the path of the rope of cigarette delivered from the former.
- 35 is a gas jet for heating the roller 34, said roller 34 forming a heater for drying the paste sticking the cigarette paper.
- 36 is the frame of the machine, of rectangular skeleton formation and having the uprights or legs 37 as part thereof. 38 and 39 are bracket extensions to said frame and uprights at the ends thereof, for the purpose of supporting various elements hereinafter more particularly referred to. The table 28 is supported on said frame 36 intermediate 40 of the length thereof and has a wheel slot 40 at one end thereof beyond the former end 32.
- 41 is a shaft journaled in the rear intermediate ones of the uprights, slightly below 50 the frame 36.
- 42 is a ribbon pulley mounted on the shaft 41 and extending upwardly slightly beyond the table top in the slot 40.
- 43 is a ribbon pulley journaled in the bracket extension 39, said pulley being of smaller diameter than the aforesaid pulley 42.
- 44 is an endless ribbon extending around the pulleys 42 and 43 and passing along 60 and through the former 27 and serving to carry the paper and tobacco through said former.
- 45 is a roll carrying the cigarette paper and journaled in the rail 46 and extending around the printing rolls 47 and 48, sup-

ported on the frame and around the ribbon pulley 43 journaled in the bracket extension 39 on to the ribbon 44 and transported by the said ribbon through the former with the tobacco therein. The paper unrolls of itself, being drawn by the pull caused by the travel of the ribbon.

51 are brackets suitably secured to the frame 36 to one side thereof, one of said brackets being intermediate of the length of the frame, and one being on one of the bracket extensions 39. Said brackets at their outer ends form shaft bearings.

52 is a horizontal shaft journaled in the bearings 51 extending from end to end of 80 the machine.

53 is a bevel gear mounted on the end of the shaft 41, adjacent to the shaft 52.

54 is a bevel pinion mounted on the shaft 52 and driving the shaft 41 through the bevel gear 53, consequently driving the endless ribbon 44 for transporting the paper and the tobacco through the former.

55 is a friction wheel longitudinally adjustable on the shaft 159, journaled in the bearings 160 supported at the upper end of the frame 157 said frame 157 being bolted to the main frame 36 and carrying the hopper box.

56 is a friction disk rigidly secured to the end of the shaft 57 and having a flat friction surface contacting the friction wheel 55, said shaft 57 extending parallel with the hopper box and at right angles to the shaft 52.

58 is a bracket rigidly secured to the outer side of the hopper box and extending upwardly and rearwardly therefrom and carrying at its upper end bearings for the shaft 57.

59 is a worm formed at the inner end of the shaft 57, said worm gearing with the worm wheel 11 hereinbefore mentioned.

60 is a vertical chain connecting the sprockets 61 and 61^a and operating the worm 59, said sprocket 61^a being fixedly mounted on the main shaft 52, thereby driving the endless carrier 1, said chain 60 connecting the ends of the shafts 52 and 159 beyond the frame.

64 is a sprocket wheel fixedly mounted on the shaft 159 and operatively connected by the chain 65 with the sprocket 26.

66 is an eccentric mounted on the shaft 159 and encircled by a strap 67, said strap having the rod 68 extending therefrom.

69 is the pivoting of the rod 68 to the frame 14, said rod connecting at its outer end to the eccentric strap 67.

73 and 74 are fixed and loose pulleys mounted on the shaft 52, said pulleys being driven in any suitable known manner.

It will now be seen that on driving the main shaft 52 all the moving parts thus far described are coincidentally driven, therefore 130

the tobacco that is transported by the carrier 1 is regulated by the reciprocating comber 13 and brushed off by the rotary brush 19 into the cigarette paper just slightly curled and 5 trough-shaped to receive it and further transported by the movement of the ribbon 44 through the former, suitably pasted and dried and delivered from the end of said former.

10 75 is a shelf slidably arranged on the upper edges of the bracket extension 38 and having the lugs 76 extending downwardly from its under side intermediate of the width and length thereof.

15 77 is a fixed shaft extending transversely across the end of the machine and secured intermediate of the length of the struts of the bracket extension 38.

78 is a rocker arm loosely mounted on the 20 shaft 77 and extending vertically thereabove and therebelow.

79 is a rod pivotally connecting the upper section of the rocker arm 78 to the lug 76.

80 is a shaft journaled in the rear end up- 25 rights of the machine intermediate of the height thereof and extending transversely across the machine.

81 is an eccentric mounted on the shaft 80 and encircled by the strap 82, said strap 82 30 being pivotally connected with the lower section of the rocker arm 78 by the rod 83, thus establishing an operating connection between the shaft 80, which is a driven shaft, and the shelf 75 whereby said shelf 35 will be reciprocated at each revolution of the shaft 80. The eccentric 81 is preferably adjustable and the form of eccentric is shown particularly in Fig. 9, in which 84 is the disk having a shaft slot 85 extending 40 from the center and terminating adjacent to one edge of said disk, the shaft in said slot being concentric in its inner position.

86 is a movable plate rectangular in shape and lying against the face of the eccentric 45 81 and having a central shaft orifice 87 and guide slots 88 adjacent to each end thereof and the boss 89 from the inner side edge thereof (see Fig. 9). 90 are suitably headed pins inserted through the slots 88 and rigidly secured in the disk 84 and retaining 50 said movable plate 86 on said disk and guiding the direction of travel of said plate.

91 is a boss from the face of the disk 84 in alinement with the boss 89 and having a 55 threaded slot therethrough parallel with the face of the disk.

92 is a cap rigidly secured on the boss 89 and retaining the end of a regulating screw in rotatable connection with the said boss 89.

60 93 is a regulating screw swivelly secured in the cap 92 having the knurled head 94 and adapted to draw the disk from its concentric position by moving it on the shaft along the slot 85, so that the length of the 65 throw of the eccentric can be very gradually

adjusted, which is a very important feature in cigarette machines on account of the various lengths of cigarettes used.

95 is an eccentric preferably of the particular form described herein and mounted on the shaft 80 a short distance from the eccentric 81 and having the rod 96 extending from its strap 97.

98 is a rocker arm mounted on the shaft 77 and horizontally disposed and at its inner end pivotally secured to the rod 96 and at its outer end pivotally secured to a rod 99, said rod 99 having a pivot 100 at its upper end.

101 are parallel posts rigidly secured to the shelf and extending upwardly therefrom having the grooved slide-ways 102 in the inner sides thereof.

103 is a block suitably formed and sliding in the slide-ways 102 pivotally secured at its lower end to the rod 99.

104 is a sleeve supported from the block 103 intermediate of the length thereof by the lateral pin 105 and forming a bearing for the rotary knife 106.

107 is a shaft carrying the knife 106 and journaled in the sleeve 104, the latter being arranged longitudinally of the machine.

108 is a pulley mounted on the shaft 107.

109 is a pulley adjustably mounted on the 95 main shaft 52 and connected to the pulley 108 by the belt 110, said belt passing over the roller 111, the latter being journaled in bearings 112 spring-held from the shelf 75, thus retaining said belt taut in all positions 100 of the knife bearing for driving said knife.

It will now be seen that a shearing mechanism is connected up to the main shaft in which the knife bearing travels up and down by means of the reciprocating block 105 103 connected through to the driven shaft 80 and the shelf 75 reciprocates coincidently consequently the said shelf will travel with the movement of the rope of cigarette, making it unnecessary to stop the travel of said 110 rope for the purpose of shearing.

113 is a grooved plate rigidly secured to the shelf 75 in alinement with the former 27 and having a grooved extension 114 terminating adjacent to the knife edge.

115 is a bell-mouthed tube rigid with and in alinement with the groove in the plate 113 and consequently in alinement with the former 27, the bell mouth 116 being at the inner end of the shelf 75, said tube being 120 rigidly secured in place to the end of the plate 113 and terminating at said plate 113, thus the rope of cigarette delivered from the former will enter the bell mouth 116 and travel along through the grooved plate 125 113 under the knife 106 and into the delivery tube 118 beyond the knife. 119 is a clamping plate correspondingly grooved to the plate 113 and completing the contour 130 of the cigarette, that is to say, the portion

lar shape of said cigarette, as these two plates will give the final press to the rope of cigarette before it is cut. The plate 119 is longitudinally hinged to the plate 113 at 5 121, consequently the lugs 122 and 123 extend considerably beyond said plate 113.

124 is a spring, here shown as of helical form and introduced between the shelf 75 and the lug 123 and exerting a constant upward pressure against said lug for retaining said clamping plate 119 in position over the cigarette.

125 is a lug extending upwardly from the shelf 75 adjacent to the lug 122, in front 15 thereof.

126 is a dog pivotally secured in the lug 125 and extending under the lug 122 and spring-held from the shelf by the spring 127, said spring 127 being of greater power 20 as regards upward pressure than the spring 124, consequently pushing upwardly on the dog 126 against the lug 122 and opening the clamping plate against the pressure of said spring 124. 128 is a finger rigidly secured to the block 103 intermediate of the height thereof, said finger 128 engaging said dog 126 at each downward movement of the block 103, thus retaining said clamping plate in position over the rope of cigarette always 25 during the operation of cutting, as the spring 127 is rendered inoperative when the finger is in engagement with the dog 126.

129 is a base screwed to the shelf 75 adjacent to the knife 106 and having the longitudinal flanges 130 at each side thereof, inwardly recessed forming the slide-way (see Fig. 7).

131 is a sliding bracket extending up from the base 129 and at its lower end sliding under the flanges 130.

132 is a boss extending upwardly from the outer end of the base 129 having a threaded orifice therethrough.

133 is a threaded pin having the knurled 45 head 134 and turning in the boss 132 and swivelly secured to the bracket 131.

135 is an arm adjustably secured to the upper end of the bracket 131 by the screw 136 and carrying at its upper end the emery

50 wheel 137 loosely mounted thereon and adapted to be adjusted in relation to the rotary knife 106 for retaining a keen edge on said knife.

In Fig. 6, a modification is shown in the 55 parts acting in conjunction with the actual shearing with the table still.

138 is a bracket rigidly secured to the shelf 75 to one side of the travel of the rope of cigarette forming at its upper end, a 60 pivot bearing. 139 is a rocker arm pivotally secured in said bracket 138 having the twisted pivot 140 at one end and at the other end a longitudinal off-set 141.

142 is a tube having the bell mouths 143 65 and 144 at the ends and the lug 145 extend-

ing downwardly from its underside and pivotally secured to the longitudinal off-set 141 of the rocker arm 139, said tube 142 being in alinement with the former 27 and receiving the rope of cigarette.

146 is a finger extending laterally from the block 103 and adapted on the lowering of the said block to come in contact with the twisted pivot 140 and rock the arm 139 and consequently slightly lift the tube 142 and buckle the rope of cigarette sufficiently to gain the necessary pause for shearing.

147 is a bell-mouthed tube in alinement with the former 27 and rigidly secured to the shelf 75 by the bracket 148 adjacent to the knife 106, and precisely similar to the clamping plate 119 in its purpose.

150 is a pressure wheel journaled in the bracket 151, said bracket being secured to the table across the former 27 so that the pressure wheel engages the tobacco and the paper immediately after it leaves the funnel hopper 23.

152 is a spur gear fixedly mounted on the shaft 41 at one end thereof outside of the 90 frame 36.

153 is a spur gear fixedly mounted on the shaft 80 at the outer end thereof in the same plane as the gear 152.

154 is an intermediate gear operatively connecting the gears 152 and 153 and loosely mounted on the shaft 155, said shaft 155 being supported in the brackets 156, the latter extending outwardly from the uprights of the machine, thus the connection between the main shaft and the shearing mechanism is established.

The hopper box 7 is supported above the main frame by the frame 157 and where said box extends beyond the main frame, it 105 is supported by said frame and the strut 158.

161 is a shield of spring material having the prongs 162 extending downwardly from and rigidly secured to the hopper box above the delivery end of the carrier 1 and adapted to prevent the sweeping by said rotary brush of strands of tobacco in advance of their actual delivery.

163 is a slot in the shaft 159 in which the 115 friction wheel 55 is keyed.

164 is a grooved pulley extension from the side face of the friction wheel 55 and rigid therewith.

165 is an arm projecting from the bearing 120 of the shaft 159 having a threaded lug 166 at the outer end.

167 is a threaded pin turning in the lug 166.

168 is a forked arm grasping the pulley 125 164 and having a threaded ring head 169 in which the pin 167 turns, thus the position of the friction on the shaft 159 in relation to the friction disk 56 may be very accurately adjusted.

- In the operation of the machine, the hopper box is loaded with tobacco and as the carrier really forms a moving platform at the bottom of the heap of tobacco, the said 5 tobacco is engaged by the small picks and carried forwardly and in order to prevent the surplus from clogging up the funnel hopper leading to the paper, the scraper or comber reciprocates constantly over said 10 carrier so that only a sufficient depth of tobacco on the carrier is brushed off by the rotary brush into the paper and as this paper is transported along and through the former and pasted on the way, the said paper, with 15 the tobacco comes out at the extremity of the former as a continuous length or rope of cigarette. The rope of cigarette passing along, enters the bell-mouth 116 and continues along under the rotary knife 106. 20 The details of the operation of the clamping plate 119 has been explained so that, all that is necessary to be said is that the clamping plate holds the rope of cigarette firmly as the knife comes down, with the consequence that the length of cigarette passing 25 beyond the knife is clipped off by the knife which rises to allow a further length to pass therebeyond. The table is, in the mean time, reciprocating, consequently, with each cut of 30 cigarette, the table moves coincidently, thereby making it quite unnecessary for any stoppage of the machine for shearing purposes, so it will be seen that in this invention the rope of cigarette is both held and traveling 35 continuously during the shearing. If the table is stationary, the form illustrated in Fig. 6 is used and in this the cutting is done while the rope is buckled as already explained. 40 The operating mechanism is very simple being from the main shaft 52, which is suitably driven, and from said main shaft are the connections to the carrier, to the brush, to the comber and to the various parts. 45 The rotation of the shaft 41 from the main shaft reciprocates the shelf carrying the shearing mechanism and raises and lowers the bearing of the knife. This is done through the gear connections from said shaft 50 to the shaft 80, which carries the eccentrics operating said mechanism. The operating connection from the main shaft to the knife has been fully explained, also as to how the knife in lowering operates 55 the clamping plate, therefore, all the parts coincidently move as soon as the main shaft starts to rotate. The details of construction may be modified to some extent, so long as the main features are retained as set forth and claimed in 60 the several claims for novelty hereinafter. What I claim as my invention is:
1. In a cigarette making machine, an endless carrier suitably driven, a sliding element disposed in a parallel plane and ad-
- jaacent to the upper surface of said carrier toward the delivery end for regulating the quantity of tobacco delivered therefrom, means for clearing said carrier of tobacco at the delivery end, and means for forming the cigarette. 70
2. In a cigarette making machine, a hopper box, an endless carrier forming a moving platform in said box, a horizontally reciprocating element disposed in said box in a parallel plane and adjacent to the upper surface of said carrier toward the delivery end thereof, for regulating the quantity of tobacco delivered therefrom, means for clearing said carrier of tobacco at the delivery end, and means for forming said tobacco delivered into cigarettes. 75
  3. In a cigarette making machine, a hopper box, an endless carrier suitably driven and forming a moving platform within said box, a comber in the form of a frame having cross strips on the underside thereof and slidably arranged in said hopper box immediately above said endless carrier toward the delivery end thereof, means for reciprocating said comber, and means for forming the tobacco delivered from said carrier into cigarettes. 80
  4. In a cigarette making machine, a hopper box, an endless carrier suitably driven and supported in said hopper box and forming a moving platform therein to receive the tobacco and having a plurality of picks extending outwardly therefrom in a forward direction, a comber formed of a frame having crossed strips on the under side thereof hinged to fold forwardly, means for reciprocating said frame immediately above said endless carrier toward the delivery end thereof and directly above said picks, and means for forming the tobacco delivered from said carrier into cigarettes. 85
  5. In a cigarette making machine, a hopper box, an endless carrier in said hopper box suitably driven and forming a moving platform therein to receive the tobacco, a comber having a frame back and cross strip teeth hinged to the under side of said back and folding to said frame only in one direction, slide-ways arranged in said hopper box for said comber immediately above said carrier adjacent to the delivery end thereof, a lever pivotally secured to the outer end of said comber, means connected with said lever for reciprocating said comber, a rotary brush journaled adjacent to the delivery end of said carrier, and brushing the tobacco therefrom, and means for forming said tobacco into cigarettes. 90
  6. In a cigarette making machine, a hopper box, an endless carrier supported within said hopper box and suitably driven and forming a moving platform within said box to receive the tobacco, a comber slidably arranged in said hopper box immediately 100

- above said carrier and formed of a back and cross strips extending from the under side of said back, a main shaft suitably driven, an arm pivotally connected to the frame of the 5 comber, an eccentric connected with said arm, a rotary brush suitably driven and clearing said carrier of the tobacco at the delivery end, and means for forming said tobacco into cigarettes.
- 10 7. In a cigarette making machine, a frame, a hopper box, a former, means for transporting the tobacco to and through said former, a vertically set wheel journaled in suitable bearings supported from the table 15 and turning loosely and engaging the length of cigarette in passage on the pasted fold, means adjacent to said wheel for heating it, and means for shearing the cigarettes.
8. In a cigarette making machine, a frame, 20 a bracket extension from the rear end, a table on the main portion thereof, a shelf slidably arranged on said bracket extension having a lug from the under side thereof, a shaft extending across the machine support- 25 ed in said bracket extension, a rocker arm mounted on said shaft, a rod pivotally connecting the upper end of said rocker arm with said lug, a shaft journaled in the main portion of the frame and suitably driven, an eccentric mounted on said shaft and connected with the other end of said rocker arm, a former supported on said table, means for 30 feeding the tobacco into said former, and a shearing mechanism on said slidable shelf.
- 35 9. In a cigarette making machine, a frame, a bracket extension from the rear end thereof, a shelf slidably arranged on said bracket extension, means for reciprocating said shelf, a knife suitably driven and supported on 40 said shelf, a bell-mouthing tube adapted to receive the length of cigarette, clamping plates between said bell-mouthing tube and said knife and operated coincidently with the downward movement of said knife, a 45 table supported on said frame, a former supported on said table, means for transporting the paper through said former, and means for feeding the tobacco on to said paper.
10. In a cigarette making machine, a frame, 50 a shelf slidably supported at the rear end thereof, means for reciprocating said shelf, a bell-mouthing tube rigidly secured at the inner end of the shelf, a plate having a longitudinal groove therein forming the base 55 of a clamping device, a plate having a corresponding longitudinal groove hinged on one side of the aforesaid plate and having on the hinge side an extension therefrom spring-held from the shelf and on the other 60 side thereof an extension therefrom spring-held from the shelf at a greater upward pressure than the aforesaid spring, a knife moving upwardly and downwardly and supported on said shelf, means from the mov- 65 able supports of said knife for engaging and holding down said top plate to said clamping mechanism at each downward stroke of the knife, a table supported on said frame, a forming mechanism supported on said table in alinement with said bell-mouth tube, and 70 means for feeding said forming mechanism.
11. In a cigarette making machine, a frame, a shelf supported at one end of said frame, a base plate secured to said shelf and forming part of a clamping mechanism having a longitudinal groove therein, a top plate hinged to said base plate and having an extension from each of its sides, a spring introduced between the extension on the hinge side and the shelf, a lug extending upwardly from the shelf adjacent to the extension on the other side of said top plate, a dog pivotally secured in said lug and extending under the latter extension, a spring exerting a stronger pressure than the aforesaid 80 spring introduced between said dog and said shelf, a rotary knife, bearings for said knife moving upwardly and downwardly, a finger from said bearings engaging said dog, at each downward stroke of the knife, means for 85 rotating said knife, a table supported on said frame, a forming mechanism supported on said table, means for feeding and transporting paper through said forming mechanism, and means for feeding the tobacco to said 90 paper.
12. In a device of the class described, in combination, a feed mechanism, a former, a frame supporting said feed mechanism and former, a shelf supported on said frame, a 100 pair of parallel vertical posts extending upwardly from said shelf having grooved inner sides, a block sliding between said posts, a bar extending outwardly from said block, a rotary knife suitably journaled and supported from said bar, a main shaft, means operatively connecting said main shaft with said rotary knife, means operatively connecting said sliding block with said main shaft, and means operatively connecting said main 110 shaft and said feed mechanism.
13. In a device of the class described, in combination, a feed mechanism, a former, a frame supporting said feed mechanism and former, a shelf supported on said frame, a 115 pair of vertical parallel posts projecting upwardly from said shelf and grooved on their inner sides, a block sliding between said posts having a lug at the lower end, a rod pivoted in said lug and extending below 120 said block, a bearing extending from said block, a rotary knife supported and journaled in said bearing, a main shaft, means for operating said knife from said main shaft, an eccentric shaft operated from said 125 main shaft, an eccentric mounted on said eccentric shaft, a rocker arm pivotally connecting said eccentric and said block rod,

and means for operating said feed mechanism from said main shaft.

14. In a device of the class described, in combination, a feed mechanism, a former, a frame supporting said feed mechanism and former, a shelf supported by said frame, vertical parallel posts extending upwardly from said shelf having grooved inner sides, a block sliding between said posts having a lug at the lower end thereof, a rod extending to said block and pivotally secured to said lug, a bearing rigid with said block and extending outwardly therefrom, a knife shaft journaled in said bearing, a rotary knife mounted on said shaft, a pulley mounted on said knife shaft, a main shaft suitably driven, a pulley on said main shaft, a belt connecting said pulley on said main shaft to said knife pulley, an eccentric shaft journaled in said frame and operatively connected to said main shaft, an eccentric mounted on said eccentric shaft, a rocker arm suitably mounted and pivotally connecting said eccentric and said block rod, a bell mouthed tube directing the length of cigarette from the former to said knife, and means from said main shaft for operating said feed mechanism.

15. In a device of the class described, in combination, a feed mechanism, a former, a frame supporting said feed mechanism and said former, a shelf supported by said frame, a vertical sliding block arranged above said table, supports for said block, a bearing supported from said block, a knife journaled in said bearing, a main shaft, means operatively connecting said main shaft and said knife, a bell-mouthed tube receiving the length of cigarette from the former, a clamping mechanism between said bell-mouthed tube and said knife, means operatively connecting the bearing support of said knife with said clamping mechanism, a supplementary shaft operatively connected with said main shaft, means from said supplementary shaft for operating said vertical sliding block, and means from said main shaft for operating said feed mechanism.

16. In a device of the class described, in combination, a feed mechanism, a former, a frame supporting said feed mechanism and former, a shelf supported by said frame, a vertically moving bearing supported above said shelf, means for supporting said bearing, means for operating said bearing, a knife supported from said bearing and suitably journaled, a main shaft, means operatively connecting said main shaft and said knife, a spring operated clamp arranged adjacent to said knife and in alignment with said former, a bell-mouthed tube leading to said clamp above said shelf, a finger rigid with said vertically movable

bearing and operatively connected in its lowermost position with said spring clamping mechanism, and means from said main shaft for operating said feed mechanism.

17. In a device of the class described, in combination, a feed mechanism, a former, a frame supporting said feed mechanism and former, a shelf supported by said frame, vertically movable bearings supported above said shelf, supports for said movable bearings, a rocker arm pivotally secured above said shelf, a bell-mouthed tube pivotally secured at one end of said rocker arm in alignment with said former, rigid means for holding the cigarette adjacent to said knife, means connected with said vertically movable bearing for operating said rocker arm at each downward movement of said knife, and means from said main shaft for operating said feed mechanism.

18. In a device of the class described, in combination, a feed mechanism, a former, a frame supporting said feed mechanism and former, a shelf supported by said frame, a bracket projecting upwardly from said shelf forming a pivot bearing at the upper end thereof, a rocker arm pivoted in said bracket having a flat extension at one end and at the other end a lateral and longitudinal off-set, a bell mouthed tube having a lug from the under side pivotally secured to the longitudinal off-set portion of said rocker arm and arranged in alignment with said former, a rotary knife, bearings for said knife, supports for said bearings, means for operating said supports to move said bearings upwardly and downwardly, a finger from said bearings engaging said flat extension, of the rocker arm at each downward movement of the knife, means for holding the cigarette adjacent to the said knife for shearing purposes, a main shaft, means for operating said knife from the main shaft, and means for operating said feed mechanism from the main shaft.

19. In a device of the class described, in combination, a frame, a shelf supported by said frame, bearings supported by said shelf, a rotary knife journaled in said bearings, a main shaft, means for operating said knife from said main shaft, a base rigidly secured to said shelf adjacent to said knife having a threaded boss at one end thereof and longitudinal under cut flanges, a threaded pin having a suitable head and turning in said boss, a plate having a corresponding lower end sliding under said flanges and extending upwardly therefrom and secured by swivel connection to said pin, an arm extending upwardly from said plate in a suitable curve and adjustably secured to said plate by a suitable screw, and an emery wheel journaled at the upper end of said arm.

20. In a device of the class described, in combination, a feed mechanism, a former, a frame supporting said feed mechanism and former, a main shaft, an eccentric shaft 6 operatively connected to said main shaft, a shearing mechanism supported by said frame, an eccentric mounted on said eccentric shaft and connected with said shearing mechanism, said eccentric being formed of 10 a disk having a slot extending from the center thereof toward the edge, a plate mounted over said slot having a shaft orifice and guide slots, headed pins extending into the disk through said guide slots and retaining 15 said plate evenly on said disk and a regulating pin in engagement with said disk and with said plate for regulating the position of the shaft in said slot, and means from said main shaft for operating the main 20 portion of said feed mechanism.

21. In a device of the class described, in combination, a feed mechanism, a former, a frame carrying said feed mechanism and former, a main shaft, an eccentric shaft operatively connected with said main shaft, a shearing mechanism supported by said frame, an eccentric on an eccentric shaft operatively connected with said shearing mechanism and slotted from the center thereof 25 and having means attached thereto for adjusting the position of the shaft in said slot, and means from the main shaft for operating said feed mechanism.

22. In a device of the class described, in combination, a feed mechanism, a former, a frame carrying said feed mechanism and former, a main shaft, an eccentric shaft, a shearing mechanism, an eccentric mounted on said eccentric shaft and operatively connected to said shearing mechanism and having a slot extending from the center of the disk toward the outer edge and a boss in alignment with said slot, said boss having a threaded orifice therethrough, a plate having 45 a shaft orifice therethrough and a boss in alignment with the aforesaid boss and slots adjacent to the outer edges thereof, suitably headed pins inserted through said side slots into said disk and forming guides, a threaded 50 pin having a knurled head inserted through said boss from the disk and having a cap secured by swivel connection on the inner end thereof, said cap being rigidly secured on said boss from the plate, and means for 55 operating said feed mechanism from the main shaft.

23. In a device of the class described, in combination, a hopper box of substantially rectangular form and having flaring upper 60 sides therefrom, an endless carrier mounted on suitable rollers, said rollers being journaled in the lower and rectangular portion of said hopper box and forming a moving platform for the tobacco, said carrier having a plurality of picks extending forwardly 65

from the surface thereof in the direction of travel of said carrier, reciprocating means supported in said hopper box immediately above said carrier for scraping rearwardly the surplus tobacco, means for operating 70 said reciprocating means, a rotary brush suitably supported and journaled and engaging the delivery end of said carrier, a funnel-shaped hopper supported immediately below the delivery end of said carrier, 75 a former extending from below said funnel-shaped hopper in a direct line therefrom, means for transporting the paper and the tobacco received from beneath the said funnel-shaped hopper in said former, means for shearing the length of cigarette formed, and 80 a frame supporting said parts.

24. In a device of the class described, in combination, a feed mechanism, a former, a frame carrying said feed mechanism, a main frame supporting said frame and former, bearings extending from the side of said main frame, a main shaft journaled in said bearings, bearings extending from said feed mechanism frame, a horizontal cross shaft journaled in said bearings, a friction disk carried at the outer end of said cross shaft, a worm formed at the inner end, a horizontal intermediate shaft supported from said feed mechanism frame, above and parallel to said main shaft and at right angles to said cross shaft, a friction wheel mounted on said intermediate shaft and horizontally adjustable thereon and engaging said friction wheel, and a chain operatively connecting said friction wheel shaft and said main shaft. 95

25. In a device of the class described, in combination, a main frame, a feed mechanism supported therefrom, a driven horizontally disposed shaft having a longitudinal key slot therein arranged, a friction wheel keyed in said slot and longitudinally adjustable therein, bearings for said shaft, a rigid arm extending out from said bearings having a threaded lug at the outer end thereof, a threaded pin having a suitable head and inserted in said threaded slot, a forked arm having a threaded ring head in which said threaded pin turns and engaging with its forked end said friction wheel, a horizontal supplementary shaft journaled at right angles to the said driven shaft, a friction disk on the end of said supplementary shaft coacting with said friction wheel, and a worm and worm wheel operatively connecting said supplementary shaft with the feed mechanism. 110

26. In a device of the class described, in combination, a main frame, a feed mechanism supported thereby having an endless carrier operating in the hopper box, a rotary brush clearing the tobacco from one end of said carrier and a shield of comb form secured to the upper part of the hopper box and extending downwardly therefrom into 125 130

proximity with the carrier adjacent to said rotary brush, and means for forming the tobacco delivered by said carrier into cigarettes.

5 27. In a device of the class described, in combination, a feed mechanism having an endless carrier operating in a hopper box, a rotary brush suitably operated at the delivery end of said carrier, a shield formed 10 with a plurality of prongs of spring material and curved inwardly and rigidly secured at one end to the upper portion of the hopper box and at the lower end extending

into proximity with the carrier adjacent to the delivery and restraining the dragging 15 of strings of tobacco by the rotary brush previous to the complete passage of said strings.

Signed at the city of Montreal, Quebec, Canada, this nineteenth day of January, 20 1911.
